UNITED STATES PATENT OFFICE.

HERMAN DÉ VRIES ROBBÉ, OF AMSTERDAM, NETHERLANDS.

CONTINUOUS CENTRIFUGAL SEPARATOR.

SPECIFICATION forming part of Letters Patent No. 614,764, dated November 22, 1898.

Application filed December 24, 1897. Serial No. 663,376. (No model.)

To all whom it may concern:

Be it known that I, HERMAN DE VRIES ROBBÉ, a subject of the Queen of Holland, residing in Amsterdam, Netherlands, have invented certain new and useful Improvements 5 in Continuous Centrifugal Separators, of which the following is a specification.

This invention has been patented in Great Britain under date of February 1, 1897, No. 10 2,597.

This invention relates to centrifugal separators such as are used in the sugar industry for the purpose of separating the sugar-crystals from the syrup and in which the action 15 is continuous.

The objects of the invention are to reduce as far as possible the labor of handling the material to be operated upon and to simplify and increase the efficiency of the machine as 20 compared with others of the same class.

With these objects in view I arrange the separator so that the material to be dried is continuously fed in at the top thereof, passes through the machine in one direction only, 25 and after having been dried passes out through the open bottom of the separator and falls directly into a suitable receptacle. I also provide various means of adjustment, as hereinafter fully described, so that the effective 30 areas of certain parts may be varied to suit the material to be treated.

The accompanying drawings illustrate such a separator embodying my improvements.

Figure I is an elevation in medial section, 35 the adjustable portions of the apparatus being shown in their mean positions. Figs. II and III are respectively fragmentary plan views of the spraying device and the driving-forks, and Fig. IV is a fragmentary section 40 on the line A A of Fig. I.

Throughout the drawings the same parts are indicated by the same reference-figures.

1 is a fixed casing inclosing the working parts of the machine and provided with the 45 channels or gutters 2 and 3, the upper gutter 2 to receive the first syrup and the lower gutter 3 to receive the second syrup. These gutters have, as shown, a falling gradient to their respective outlets 2' and 3'.

4 is a cylindrical rotating perforated sheet-metal casing or open-bottomed basket carried by a number of T-bars 5 from a helical-armed

steel casting 6, securely keyed to the main spindle 7, a perforated-curved plate 8 being employed to connect the basket 4 to the bars 5. 55

9 is a conical rotating perforated sheet-metal casing or open-bottomed basket carried from an armed steel casting 10, which is fitted on and adapted to slide axially on the cylindrical boss 6' of the casting 6, the axial 60 position of the conical basket relatively to the cylindrical basket being adjusted by the lock-nuts shown. The double thickness of the baskets, as shown in the drawings, represents the outer perforated metal and the 65 inner lining of gauze, the latter being held in position by the rings shown.

No details are shown of the driving means or the bearings of the main spindle, as these may be of the ordinary kind. The spindle 70 may either be overdriven or underdriven, as may be more convenient, although the former is usually preferable.

11 is a circular plate, preferably coned, as shown, carried from the boss 12, which fits 75 upon and is adapted to slide axially on the boss 10' of the casting 10, the axial position of the plate relatively to the conical basket being adjusted by the lock-nuts shown. A ring 13, which serves to hold the gauze lining, 80 also serves, in conjunction with the adjustable plate 11, to form an annular passage of adjustable radial width through which the material has to pass downward and by which its descent may be controlled. It will be 85 noticed that the plate 11, being carried from the boss 10', which carries the conical basket, moves with the latter once its relative position thereto is determined by adjusting the lock-nuts screwed on the boss 10'.

A further 90 means of controlling the descent of the material is afforded by the combination of the cylindrical basket 4 and the conical basket 9, adjustable relatively thereto, as the descent 95 of the material on the conical basket is assisted by centrifugal force, while the material on the cylindrical basket is not so impelled, and the effective area of the basket 4 can be decreased or increased, accordingly as more or less of it is overlapped by the conical basket. 100

14 are driving-forks attached to the conical basket 9, the open ends of which embrace the bars or arms 5, and so transmit the driving force from the latter to the conical basket.

A plan view of one of the forks is shown in Fig. III.

15 is the spray-pipe supplied by the pipe 16, and 17 is a tray provided with a drain-pipe 18. These pipes and tray are shown in fragmentary plan in Fig. II.

I provide an annular plate 19, which, in conjunction with the ring 20 on the conical basket, serves to guide the first syrup into the gutter 2, and in order that the height of the plate 19 may be adjusted as the conical basket is raised or lowered I carry it by means of adjusting-screws 21 and provide depending plates 22, which, in conjunction with the plate 23, form an adjustable side wall for the gutter 2. The material after having passed down through the machine is received in a hopper 24, being guided thereto by a conical guide 25. The second syrup is guided to the gutter 3 by the peripheral plate 26.

The outer fixed casing 1 is provided with covers 27, and the upper conical portion 28 of the casing may be formed in halves with a suitable joint.

25 When the material is first fed into the machine, its passage downward is facilitated by the propelling action of the helical arms of the casting 6. A section of these arms on the line A A is shown in Fig. IV. It will be seen that the action is continuous and unidirectional and that in the arrangement shown the passage of the material through the apparatus is at each point in its path assisted by gravity and that the material may be directly collected in a removable receptacle, which features very much facilitate the handling of the sugar.

Although I have described the machine with reference to the drying of sugar, it may, of course, with slight modifications be applied to dry other materials.

Having now fully described my invention, what I claim, and desire to secure by Letters Patent, is—

45 1. In combination; a fixed outer casing provided with upper and lower gutters; a rotating conical basket, open at top and bottom and placed with its larger end lowermost; and an open-bottomed rotating cylindrical basket, 50 open at top and bottom, forming a prolongation of the conical basket downward and carried from the same spindle; substantially as described and illustrated.

2. In combination; a fixed outer casing provided with upper and lower gutters; a rotating conical basket, open at top and bottom and placed with its larger end lowermost; an open-bottomed rotating cylindrical basket 55 overlapping the lower end of the conical basket and carried from the same spindle; and means for axially adjusting the conical basket relatively to the cylindrical basket, so as

to regulate the amount of overlapping; substantially as described and illustrated.

3. In combination; a central spindle; an 65 open-bottomed cylindrical basket carried by an open framework from a central armed piece secured to the said spindle; a second central armed piece fitting on the boss of the said first armed piece and axially adjustable 70 thereon; and a conical basket, open at top and bottom, carried from the second central piece, so as to be adjustably overlapped by the cylindrical basket; substantially as described.

4. In combination; a rotating conical basket open at top and bottom and placed with its larger end lowermost; an open-bottomed rotating cylindrical basket overlapping the lower end of the conical basket; and a circular plate or diaphragm placed within the conical basket; the three parts being axially adjustable relatively to each other; substantially as described.

5. In combination with the spindle, the axially-adjustable conical basket, the cylindrical basket, and the circular diaphragm, a central member secured to the spindle, the said member serving as the means for carrying the cylindrical basket forming the inlet for the material, and provided with helical arms to assist the descent of the latter; substantially as described and illustrated.

6. In combination; a fixed outer casing with gutters; a central spindle; a cylindrical 95 open-bottomed basket carried by an open framework from a central armed member secured to the said spindle; a conical basket open at top and bottom fitting within the cylindrical basket and carried from a second central armed piece fitting and axially adjustable on the boss of the first central piece; and a circular diaphragm placed within the conical basket and carried by a central piece fitting and axially adjustable on the boss of the second-mentioned central piece, so that the said diaphragm although partaking in the movement of the conical basket is axially adjustable with respect to the latter; substantially as described and illustrated.

7. In combination with the outer fixed casing, having the upper and lower gutters, and the rotating parts of the separator; the vertically-adjustable deflecting-plate 19 carried by said casing and the depending plates 22 attached to said plate 19; substantially as described and illustrated.

In testimony whereof I have hereunto set my hand in the presence of two subscribing witnesses.
